UNITED STATES PATENT OFFICE

ALFRED CRAWFORD, OF NEW BRUNSWICK, NEW JERSEY, ASSIGNOR TO CRAWFORD MANUFACTURING COMPANY, OF NEW BRUNSWICK, NEW JERSEY, A CORPORATION OF NEW JERSEY

ELECTRIC STOP MOTION FOR KNITTING MACHINES

Application filed April 1, 1930. Serial No. 440,784.

This invention relates to an electric stop motion for knitting machines and constitutes an improvement to a somewhat similar device shown and described in a prior United States patent to E. S. Hineline, No. 1,417,914, dated May 30, 1922.

The present invention consists of the adaptation of certain principles disclosed in the above mentioned patent to a stop motion of the general character shown and described in a prior United States patent to Frank Crawford, Sr., No. 1,684,308, dated September 11, 1928.

The object of the present invention is to provide a device which will have a greater scope of utility and greater sensitiveness than the device shown in the first mentioned patent and at the same time be of a rather simple construction.

The nature of the construction of the device shown in Patent No. 1,417,914 limits the utility of the device to machines using relatively heavy knitting threads, but by the adaptation of the principles thereof to the extremely sensitive device disclosed in Patent No. 1,684,308 threads of the lighter weights may be employed, for example, threads of the nature known in the knitting art as "two thread silk", or its equivalent in "rayon" or other threads.

The device shown in Patent No. 1,417,914, by the nature of its construction, is limited to machines employing four knitting threads, or multiples of two, whereas by adapting the general principles of such a device to the apparatus shown in Patent No. 1,684,308 any desired number of knitting threads may be employed.

Another object of the present invention is to provide means whereby the electric current is automatically cut off from the entire device every time the stop motion is tripped, either by the breaking of a knitting thread, a condition causing abnormal tension to be applied to one or more of the knitting threads, or by abnormal slackening of any of the threads which may occur while a machine is standing idle for a prolonged period of time, such as overnight or between two regular working periods.

In the drawing of the present application:

Fig. 1 is a perspective view of the stop motion embodying the features of the present invention;

Fig. 2 is a plan view of the upper control head which is adapted to be actuated by abnormal tension conditions arising in the knitting threads;

Fig. 3 is a side elevation of the mechanism shown in Fig. 2 with the casing broken away for the purpose of illustration;

Fig. 4 is a fragmentary sectional elevation taken on the line 4-4, Fig. 2;

Fig. 5 is a plan view of the lower control head adapted to be actuated by the breaking of a knitting thread or by excessive slackness developing therein;

Fig. 6 is a side elevation of the mechanism shown in Fig. 5, with the casing broken away for the purpose of illustration;

Fig. 7 is a perspective view of the safety switch mechanism shown in Figs. 5 and 6; and

Fig. 8 is a wiring diagram.

As shown in Fig. 1, the device in general comprises a standard 10 rigidly secured to and projecting upwardly from the main bed plate 1 of a conventional type of knitting machine, which is provided with a suitable lever 2 adapted for shifting the driving belt 80 of the knitting machine from the tight to the loose pulley thereof, when the stop motion is actuated, to stop the machine.

Mounted on the upper end of the standard 10 is the lower control head or stop motion 11, which comprises a casing 12 and a cover 13 therefor.

Mounted in the cover 13 of the lower control head 11 and substantially in axial alignment with the standard 10 is a second or upper standard 14, which constitutes a continuation of the lower standard 10.

On the upper end of the upper standard 14 is mounted the upper control head or stop motion 15, which comprises a suitable casing 16 and a cover 17 therefor.

Radiating from the casing 16 of the upper control head 15 is a plurality of projecting stumps 18, 18 on each of which is pivotally mounted, as at 19, a tension trip finger 20.

In each of the stumps 18 is rotatably mounted a trip rod 21 having a lever 22 at its outer end adapted to engage the underside of the trip finger 20. On the inner end of each trip rod 21 is a double ended lever 23, one end of which is provided with a crank 24 and to opposite end of which is secured one end of a spring 25.

The opposite end of the spring 25 is secured to the outer end of a tension regulating arm 26, pivoted at 27 to a plate 28 disposed substantially parallel to a base plate 29 which is secured in the bottom of the casing 16. The plate 28 is spaced apart from the plate 29 by an intermediate hub 30.

Secured in the hub 30 is a post 31, in the upper end of which is rotatably mounted a pivot stud 32 for and secured to a horizontally disposed actuating disc 33.

The disc 33 is provided with an interrupted depending flange 34, which is notched at spaced intervals, as indicated at 35, 35, into each of which projects one of the cranks 24 of the levers 23 on the inner ends of the trip rods 21.

The springs 25 tend to turn the rods 21 in a clockwise direction, as viewed from the interior of the casing 16, which causes the levers 22 to turn the trip fingers upwardly about their pivots 29, the trip fingers engaging abutments 36 which maintains the whole chain of elements in a predetermined operative position.

The interrupted flange 34 of the disc 33 is provided with a notch 37 in which is disposed the upper end of a lever 38. The lever 38 is pivoted at 39 to a bracket 40 which is secured to the base plate 29 in the bottom of the casing 16.

The lever 38 at one side of its pivot 39 is provided with a counterbalance 41, which tends to turn the lever 38 about its pivot and thereby turn the disc 33 in a clockwise direction, as viewed from above, which maintains the sides 42 of the disc notches 35 in contact with the cranks 24 of the trip rods 21.

At the opposite side of its pivot 39, the lever 38 is provided with a lateral projection 43, at the outer end of which is secured an insulating block 44. In the insulating block 44 is secured an inverted U-shaped contact element 45. The contact element 45 is provided with a pair of spaced depending contacts 46, 46, which respectively are positioned in wells 47, 47 formed in an insulating block 48. The insulating block 48 is adjustably mounted in the bottom of the casing 16.

In each of the wells 47 is provided a suitable quantity of mercury or other fluid-like substance 50 capable of efficiently conducting electric current.

As shown in Fig. 4, the lower ends of the contacts 46, 46 are disposed slightly above the surface of the conducting medium 50 in

each well. The tension of the springs 25, 25 and the counterbalancing of the lever 38 is so minutely adjusted that these contacts are normally held in the position shown when the knitting machine is in operation, the minute counterbalancing of the lever 38 being augmented by a light spring 51, shown in Figs. 2, 3 and 4.

The insulating block 48 passes through suitable openings formed in the base plate 29 and the bottom of the casing 16 and is provided outside the casing with a laterally extending projection 52 through which passes a supporting screw 53. The screw 53 is threaded into the bottom of the casing 16, the base plate 29, or both, for raising the block 48 in the casing and thereby adjusting the position of the upper surface of the conducting mediums 50, 50 relative to the lower ends of the contacts 46, 46. A control screw 54 is threaded through the extension 52 of the block 48 and bears against the lower side of the bottom of the casing 16, whereby the block 48 may be secured in its adjusted position or moved in an opposite direction in making the adjustment.

Secured to the base plate 29, adjacent the insulating block 48, or formed integral with the said block 48, is another insulating block 55 which is provided with stationary contacts 56 and 57. These fixed contacts extend into the wells 47, 47 and into the conducting medium therein, at all times.

The fixed contacts 56 and 57 are respectively connected to current-conducting wires 58 and 59, for purposes hereinafter set forth. The upper standard 14, in the present instance, is hollow and the wires 58 and 59 pass from the casing 16 of the upper control head 15 through the upper standard 14 to the lower control head 11.

The lower control head 11, as above noted, comprises the casing 12 and cover 13. As shown in Fig. 6, the wires 58 and 59 terminate in an insulating block 60 secured to the underside of the cover 13, the wires being electrically connected to suitable prongs 61 which are adapted respectively to enter openings 62, 62 formed in an insulating block 63 secured to the side wall of the casing 12, the openings 62, 62 being provided with suitable spring contacts 64, 64 which engage the tips 61 to make electrical contact therewith.

With this construction the upper part of the apparatus may be readily removed from the lower part thereof to facilitate shipping.

Radiating from the casing 12 of the lower control head 11 is a plurality of arms 118 each having rotatably mounted therein a trip rod 121. On the inner end of each trip rod 121 is a crank 124 adapted to lie within and engage one side 142 of a notch 135 formed in an interrupted depending flange 134 of an actuating disc 133.

On the outer end of each arm 118 is a

thread guide 70 comprising a stationary plate which is U-shaped in plan. In the respective sides 71, 71 of the U-shaped plate 70 are formed slots 72, 72a.

8 On the outer end of each trip rod 121 is a drop lever 73 having fingers 74, 74 which extend into the slots 72 formed in one of the side plates 71.

The knitting thread α passes between the 10 plate 71 and the finger 74, which holds the drop lever 73 in a substantially vertical position and maintains the trip rod 121 and the crank 124 thereon in a predetermined operative position.

15 The disc 133 is rotatably mounted in a post 131 located in the casing 12, a spring 75, which is wound about the pivot stud 132 of the disc 133 and has one end secured in the post 131 and its opposite end in engagement 20 with a lug 76 formed on the disc 133, tends to rotate the disc 133 in a clockwise direction, as viewed from above, to hold the sides 142 of the notches 135 in contact with the cranks 124 of the trip rods 118.

25 Secured in the bottom of the casing 12 is a base plate 129, on which is secured a bracket 140. Pivotaly mounted at 139 to the bracket 140 is a lever 138. The upper end of this lever 138 lies in a notch 137 of the depending 30 flange 134 of the disc 133.

The lever 138 at one side of its pivot 139 is provided with a counterbalance 141 and at the opposite side of its pivot with an extension 143 on which is mounted an insulating block 144. The insulating block 144 is provided with an inverted U-shaped contact element 145. The contact element 145, like the contact element 45 above noted, comprises two depending contacts 146, 146 which 40 extend into wells 147, 147 formed in an insulating block 148.

Like the block 48 above noted, the block 148 extends through openings in the base plate 129 and in the bottom of the casing 45 12, and is provided with an extension 152 and adjusting screws 153 and 154, which function in exactly the same manner as the screws 53 and 54 above noted.

The wells 147, 147 each contain a quantity 50 of mercury 150, or other electric-conducting fluid-like substance, and projecting into the conducting medium in the wells 147, 147 respectively are fixed contacts 156, 157.

The fixed contact 156 is connected by a 55 wire 58a to the spring terminal 64 in the socket 62 into which the tip 61 of the wire 58 extends, thus making a direct electrical connection from the fixed contact 56 of the upper control head 11 to the fixed contact 156 60 in the lower control head 11.

The fixed contact 157 is connected by a 65 wire 159a to one terminal 160 of an electric motor which, in the present instance, is in the form of an electro-magnet 161 which is securely mounted in the casing 12. The ter-

70 minal 160 of the electro-magnet 161 is also connected by a wire 59a to the spring terminal 64 in the socket 62 in which is positioned the tip 61 of the wire 59, which leads from the upper fixed contact 57.

75 Thus it will be noted that the fixed contacts 57 and 157 are directly connected to one terminal 160 of the electro-magnet 161, and the fixed contacts 56 and 156 are connected directly with each other and with one wire 158 of a power line, the other wire 159 of the said power line being connected, through a safety switch 165, to the second terminal 162 of the electro-magnet 161.

80 The safety switch 165 comprises an insulating block 165a which is secured in the casing 12. A knife switch blade 166 is pivoted at 167 to the block 165a and normally engages at its opposite ends with contacts 168 and 169, respectively, to which the ends of the split 85 wire 159 are respectively connected. A spring 170 tends to open the switch 165 at all time but is restricted in its efforts by mechanism hereinafter described.

85 Pivotaly mounted at 171 on a bracket 172 90 located adjacent the electro-magnet 161 is a bell-crank lever 173, one arm 174 of which lies directly above the core 175 of the electro-magnet. The second arm 176 of the bell-crank lever 173 is adapted to engage an arm 95 177 of a latch 178 which is pivoted at 179 to the base plate 129.

90 The latch 178 is provided with a hook 180 which engages the outer end of a control lever 181 secured to the actuating shaft 182 of the 100 stop motion. A spring 183 wound about the actuating shaft 182, tends to turn the shaft in a clockwise direction at all times, to actuate the stop motion to stop the machine.

95 The actuating shaft 182 is rotatably mounted at its upper end in the casing 12 of the 10 lower control head 11 and at its lower end in a bearing 182a carried by the lower standard 10 adjacent the bed plate 1 of the knitting machine.

100 On the lower end of the actuating shaft 182 is secured a lever 185, in the outer end of which is slidably mounted one end of a link 186 having an abutment 187 thereon which 115 is engaged by the lever 185. The opposite end of the link 186 is connected to one arm 187 of a bell-crank lever 188, which is pivoted at 199 to the bed plate 1 of the knitting machine.

110 The second arm 190 of the bell-crank lever 188 has a shoulder 191 against which the outer end of the belt shifter arm 2 normally bears, under pressure exerted by a spring (not shown), but which, when the lever 2 is released by the bell-crank arm 190 moving 115 away from the lever 2, actuates the belt shifter (not shown) in a manner to move the driving belt from the tight to the loose pulley of the knitting machine to stop the said machine.

The safety switch blade 166 is held in operating position by a lug 195, composed of insulating material, secured to the actuating lever 181. The lug 195 as shown in Fig. 5, 5 bears against one end of the switch blade 166 and holds it in engagement with the contacts 168, 169 against the action of the spring 170.

When the knitting machine is in operation the elements of the stop motion are in the 10 positions shown in the drawings, the knitting threads α , α passing from the cones α^1 , α^1 , through the thread guides 70, up and over the trip fingers 20 and then down through guides 196 to the knitting needles (not shown).

15 If for any reason abnormal tension is applied to any one or more of the threads α , the finger 20 over which such thread passes will be turned about its pivot 19, thereby 20 rocking the trip rod 21, which through the crank 24, will turn the disc 33 in a counter-clockwise direction. Turning of the disc 33 in a counter clockwise direction will rock the lever 38 about its pivot, causing the ends 25 of the depending contacts 46, 46 to dip into the mercury in the wells 47, 47 which completes the electric circuit to the electro-magnet 161.

If one of the threads α should break or 22 become abnormally slack, the drop arm 73 which is controlled by such thread will be released and will fall, thereby turning the trip rod 121 on which it is mounted. Turning 28 of the trip rod 121 will, through the crank 124, turn the disc 133 in a counter clockwise direction, thereby turning the lever 138 about its pivot, permitting the depending contacts 146, 146 to dip into the mercury 150, 150 in the wells 147, 147, thus completing the circuit 35 to the electro-magnet 161.

42 When the electro-magnet 161 is energized, by the operation of either the disc 33 in the upper control head or the disc 133 in the lower control head, as above noted, the magnet immediately pulls down on the arm 174 of the bell-crank lever 173, turning the said bell-crank lever 173 on its pivot 171, so that the second arm 176 thereof will strike the arm 177 of the latch 178. The latch 178 is thereby turned on its pivot 179, causing the hook 180 of the latch to release the actuating 50 arm 181 of the actuating shaft 182.

The spring 183 then turns the shaft 182 causing the lever 185 to pull on the link 186, which turns the bell-crank 188 on its pivot 189, the shoulder 191 being thereby removed from in front of the belt-shifting lever 2, permitting the said lever 2 to effect a shifting of the drive belt from the tight to the 60 loose pulley, as above noted.

As the actuating shaft 182 turns, the lug 195 on the lever 181 moves away from the switch blade 166, which immediately turns about its pivot under the influence of the 65 spring 170, thereby breaking the electric con-

tact between the switch blade 166 and the contacts 168, 169.

The whole apparatus is thereby wholly disconnected from the source of electric energy 70 by which the magnet 161 is operated.

When the actuating lever 181 is released from the latch 178 and turns in a clockwise direction under the influence of the spring 183 to effect the stopping of the machine, an arm 184 on the actuating lever, which normally lies in a notch 184^a in the depending flange of the disc 133, turns the said disc 133 in a clockwise direction to immediately and automatically reset the drop arms 73, 73. The contacts 146, 146 are at the same time removed 80 from the mercury contacts 150, 150.

To reset the device the actuating shaft 182 is turned in a reverse direction by manually operating the resetting lever 196 which is secured to the actuating shaft 182. Such turning of the shaft 182 causes the tip of the actuating lever 181 to be reengaged by the hook 180 of the latch 178, the lug 195 again engaging the knife switch blade 166 and turning it about its pivot 167 until the opposite ends of the switch blade engage the contacts 168, 169 respectively, it being understood that the cause for the tripping of the stop motion has been removed, permitting the drop levers and tension fingers to resume their normal operative positions above noted.

Obviously, the magnet 161 and the latch arm 177 could be so arranged that the magnet would act directly on the said latch arm and thus eliminate the bell-crank lever 173. This could be accomplished by positioning the magnet 161 in a position with its axis lying in a horizontal plane with the end of the core 175 adjacent the latch arm 177.

While I have described a magnet with a fixed core, obviously a movable plunger solenoid could be employed with the said plunger operatively connected to either the arm 174 of the bell-crank lever 173 or directly to the 110 arm 177 of the latch 178.

The vertical adjustment of the mercury pots 48 and 148, relative to the ends of the contacts 46, 46 and 146, 146, makes it possible to regulate the extent of permissible ineffective relative movement between the mercury contacts and the movable contacts co-operating therewith, to time the actuation of the stop motion, and, due to the construction shown, this timing may be readily made from 115 the outside of the casing without disturbing any of the operating parts of the mechanism.

I claim:

1. In a stop motion, the combination of a 125 plurality of thread-controlled trip elements, an actuating disc common to all said trip elements and adapted to be actuated by any thereof, a normally open electric switch controlled by said actuating disc and adapted to be closed thereby for completing an electric 130

trolled by said actuating disc and adapted to be closed thereby for completing an electric circuit in which said switch is included, to effect the stopping of the machine to which
 5 the stop motion is applied, when an abnormal condition arises in any of the trip-controlling threads, an electro-magnet included in said circuit, an actuating lever, means tending to turn said lever in one direction,
 10 a retaining latch for and engaging said actuating lever, and a bell-crank lever having one of its arms engaging said latch and its other arm overlying and adapted to be actuated by said electro-magnet to release said
 15 latch from the actuating lever.

9. In a stop motion, the combination of a plurality of thread-controlled trip elements, an actuating disc common to all said trip elements and adapted to be actuated by any
 20 thereof, a normally open electric switch controlled by said actuating disc and adapted to be closed thereby for completing an electric circuit in which said switch is included, to effect the stopping of the machine to which
 25 the stop motion is applied, when an abnormal condition arises in any of the trip-controlling threads, an electro-magnet included in said circuit, an actuating lever, means tending to turn said lever in one direction, a re-
 30 taining latch for and engaging said actuating lever, a bell-crank lever having one of its arms engaging said latch and its other arm overlying and adapted to be actuated by said electro-magnet to release said latch from
 35 the actuating lever, and a normally closed switch included in said circuit, means tending to open said normally closed switch at all times, said normally closed switch being normally retained in its closed position by
 40 engagement with said actuating lever.

10. In a stop motion, the combination of an upper control head and a lower control head, a plurality of thread controlled trip elements in each of said heads, an actuating
 45 disc in each head common to all and adapted to be actuated by any of the trip elements therein, an electric switch in each head controlled by the disc therein, an electric motor common to both heads and included in
 50 one side of an electric circuit with said switches and adapted to be controlled by either of said switches to effect the stopping of the machine to which the stop motion is applied, and an automatic safety switch in
 55 and adapted to open the opposite side of said electric circuit including the first two said switches and the said motor subsequent to the actuation of said motor.

11. In a stop motion, the combination of a
 60 series of pivotally mounted trip elements, a pivotally mounted actuating element common to all and engaged by each of the said trip elements, an electric switch comprising a pivotally mounted lever engaged by said common
 65 actuating element, an electric contact carried

by said switch lever at one side of its pivot, and a counterweight carried by the said switch lever at the opposite side of its pivot, whereby the said pivotally mounted elements are maintained in substantially balanced relation to each other. 70

12. In a stop motion, the combination of a series of pivotally mounted trip elements, a pivotally mounted actuating element common to all and engaged by each of the said trip elements, an electric switch comprising a pivotally mounted lever engaged by said common actuating element, an electric contact carried by said switch lever at one side of its pivot, a pair of relatively fixed electric contacts adapted to be engaged by said movable contact, and a counterweight carried by the said switch lever at the opposite side of its pivot, whereby the said pivotally mounted elements are maintained in substantially balanced relation to each other, and the said movable contact is normally maintained in open circuit relation to said fixed contacts. 80

13. In a stop motion, the combination of a series of pivotally mounted trip elements, a pivotally mounted actuating element common to all and engaged by each of the said trip elements, an electric switch comprising a pivotally mounted lever engaged by said common actuating element, an electric contact carried by said switch lever at one side of its pivot, a counterweight carried by the said switch lever at the opposite side of its pivot, whereby the said pivotally mounted elements are maintained in substantially balanced relation to each other, and an adjustable spring tension augmenting the said counterweight. 90

14. In a stop motion, the combination of a casing, a plurality of thread-controlled trip elements extending into said casing, an actuating disc in said casing and common to all said trip elements and adapted to be actuated by any thereof, an electric switch controlled by said actuating disc for controlling an electric circuit in which said switch is included, to effect the stopping of the machine to which the stop motion is applied, when an abnormal condition arises in any of the trip-controlling threads, said switch comprising an insulating block mounted in said casing and having a well containing a suitable fluid-like electric conducting medium therein to which one side of said circuit is connected, a movable contact operatively connected to said disc and normally lying above the surface of said conducting medium, and means for adjusting the said insulating block relative to the casing and to said movable contact therein, to regulate the extent of permissible ineffective relative movement between said switch elements under normal operating conditions. 100

15. In a stop motion, the combination of a plurality of thread-controlled trip elements, an actuating disc common to all said trip elements and adapted to be actuated by any 110

thereof, a normally open electric switch controlled by said actuating disc and adapted to be closed thereby for completing an electric circuit in which said switch is included, to effect the stopping of the machine to which the stop motion is applied, when an abnormal condition arises in any of the trip-controlling threads, an electric motor included in said circuit, an actuating lever, a latch engaging 10 said lever, means actuated by said motor to release said latch from said lever upon the closing of the circuit by said normally open switch, and an arm on said actuating lever adapted to engage said disc and return the 15 said disc and the said trip elements to their normal positions, when said actuating lever is released from said latch.

ALFRED CRAWFORD.
